UNITED STATES PATENT OFFICE

100,913

DESIGN FOR A DISPLAY CARD FOR DOLLS

Ernest Bocchino, Clifton, N. J.

Application June 11, 1936, Serial No. 63,226

Term of patent 3½ years

To all whom it may concern:

Be it known that I, Ernest Bocchino, a citizen of the United States, residing at Clifton, in the county of Passaic and State of New Jersey, have invented a new, original, and ornamental Design for a Display Card for Dolls, of which the following is a specification, reference being had to the accompanying drawing, forming a part thereof, and in which:

The figure is a front elevational view of the display card for dolls, showing my design.

The display card is of no material thickness, flat representations of fanciful dolls being secured to the apertured face thereof.

I claim—

The ornamental design for a display card for dolls, as shown and described.

ERNEST BOCCHINO.
